WINDOW

Henry Leiser, % 3-D Windows, Inc., 3285 S. Dayton St.,
Denver, Colo. 80222
Filed Dec. 29, 1964, Ser. No. 421,832
14 Claims. (Cl. 160—92)

The present invention relates to a window, and more particularly to a window having a hinged sash which is slidably connected with a hinged screen frame.

For many years, the vast majority of windows utilized were sliding, double-hung windows. Since these windows required separate screening, they were relatively expensive. Further, they were inflexible from an esthetic point of view, and at the present time do not offer the architect a suitably new and esthetic choice in the construction of a building.

Jalousie windows are known to have many parts, are relatively expensive, and are, at best, extremely difficult if not impossible to suitably weatherproof. Another type of window which has received considerable attention is those in which a glazed sash was pivotally mounted in a frame. Such windows have been unsuitable for a variety of reasons, including the necessity to provide a triangular side or jamb element which extended either into the room, or exteriorly of the building. Further, such windows were difficult to remove for clearing and were often not safe against unauthorized entry.

An object of the present invention is to provide a window having a pleasing appearance.

Another object of the present invention is to provide a pivoted sash window which does not require triangular side elements.

Another object of the present invention is to provide a window having few parts, and which is easy and economical to manufacture and install.

Another object of the present invention is the provision of a window permitting adequate ventilation and effective weatherproofing.

Still another object of the present invention is to provide a window particularly suited for use as a basement window.

Yet another object of the present invention is the provision of a window which is safe against unauthorized entry.

A still further object of the present invention is to provide a window in which the glazed sash may be readily removed for cleaning.

Other objects and many of the attendant advantages of the present invention will be readily understood from the following specification and drawings wherein:

FIGURE 1 is a cross sectional view, with parts removed, of a window in accordance with the present invention.

FIGURE 2 is cross sectional view taken on line 2—2 of FIGURE 1.

FIGURE 3 is a view taken on line 3—3 of FIGURE 2.

FIGURE 4 is a perspective view of another embodiment of the window of the present invention.

FIGURE 5 is a perspective of still another embodiment of a window embodying the present invention.

Referring now to the drawings, wherein like or corresponding reference numerals are used to designate like or corresponding parts throughout the several views, there is shown in FIGURE 1 a window generally designated 10, there being shown a header 11, a sill 12, a jamb 13, it being understood that a similar jamb is provided, but is not shown in FIGURE 1. Jamb 13 is a generally planar element of substantially rectangular configuration, is being understood that the two jambs

2

together with the header 11 and sill 12 form an open frame.

Secured to the header 11 is a support 14 which includes a bearing 16, the axis of which extends transversely of the window opening between the two jambs. In similar manner, the sill 12 is provided with a support 17 that includes a bearing 18. Bearing 18 has an axis which is generally parallel to the axis of bearing 16, and is spaced generally therebelow. Further, it will be understood that the window 10 is positioned in a building so that the building exterior is to the left, and the building interior is to the right, as viewed in FIGURE 1, so that the upper bearing 16 and lower bearing 18 are adjacent the outer edges of the header 11 and sill 12, respectively.

Journaled on the lower bearing 18 is a glazed sash generally designated 20, sash 20 including along its lower edge a block 21 in cooperation with the lower bearing 18. Generally above the glazed sash 20 is a screened frame 30 which is suitably curved at one edge 31 so as to cooperate with and be journaled on the upper bearing 16, screened frame 30 extending generally inwardly of upper bearing 16.

Referring now to FIGURE 2, there is shown the top rail 22 of the glazed sash 20. A connecting element 23 having at its upper end a sphere 24 is positioned in the top rail 22, it being understood that a similar connecting element 23 is provided at the opposite end of the top rail 22. A weather strip 26 is also held in the top rail 22, and extends between the connecting elements 23. In FIGURE 3, it will be seen that the top rail 22 is provided with a slot 27 for holding both the weather strip 26 and the two connecting elements 23.

The screened frame 30 is provided with a generally cylindrical slot 32 which connects with a substantially rectangular slot 33, slot 33 opening out of the bottom of the screened frame 30 in the side rail 34 of screened frame 30. As will be understood, screened frame 30 comprises two such side rails of substantially identical configuration, so that there are two cylindrical slots extending in the screened frame 30, each receiving a sphere 24 in sliding relationship. As will be understood from FIGURE 1, the cylindrical slots 32 are generally perpendicular to the axis of upper bearing 16.

The screened frame 30 is provided with a slot generally designated 36 for receiving the screen 37 and a resilient generally cylindrical securing element 38.

Referring again to FIGURE 1, there is secured to the jamb 13 by a screw or rivet 41 a locking element generally designated 40 comprising a relatively long central part 43 and a pair of fingers 44 and 46 at either end thereof. A removable peg 42 holds locking element 40 in the full line position shown, and thereby limits the movement of screened frame upwardly, and also limits the movement of glazed sash 20 inwardly. Upon removal of peg 42, however, the locking element 40 may be moved to the dotted line position shown, to thereby permit the glazed sash 20 to be swung into a substantially horizontal position, the sphere 24 passing out of the open end of slot 32 at each side of the screened frame 30.

A weather strip element 47 extends along jamb 13 generally between the upper bearing 16 and lower bearing 18, in position to engage the side rails of the glazed sash 20 when glazed sash 20 is moved to the dotted line position shown in FIGURE 1. In addition, each of the side rails of glazed sash 20 may be provided with weather stripping, as is shown in FIGURES 4 and 5, and the glazed sash 20 may be provided with a suitable lock, such as a slide bolt, to engage in a hole in a jamb, to lock the glazed sash 20 in the dotted line position shown.

In operation, to provide ventilation, the glazed sash 20 is rotated on lower pivot 18 to expose more or less of the screened frame 30, the spheres 24 at this time sliding in the slots 32 and the screened frame 30 rotating on the upper bearing 16 in harmony therewith. Due to the locking element 40, the rotational movement of the glazed sash 20 will be stopped prior to the disengagement of the spheres 24 from the slots 32. To close the window, rotational movement to the dotted line position is effected, thereby engaging the outwardly facing surfaces of the rails and stiles of glazed sash 20 with suitable weather stripping elements, such as weather strip 47. The window 10 is thereby closed, and suitably weather stripped against drafts. In this position, of course, the weather strip 26 engages with the front or outer rail of the screened frame 30. As will be understood, the locking element 40 may be moved to the dotted line position by removal of peg 42, to thereby permit removal of glazed sash 20 for cleaning, etc.

Referring now to FIGURE 4, there is shown a screened frame 50 including a laterally facing slot 51 on the lower edge thereof, slot 51 extending generally perpendicularly to upper bearing 16. The glazed sash 55 has a plate 56 secured to the face thereof by screws or the like, plate 56 having a laterally extending connecting finger 57 positioned in the slot 51 for sliding movement therein. The glazed sash 55 is provided on its side edge with a weather stripping element 58.

Referring now to FIGURE 5 there is shown another embodiment of the present invention, the screened frame 50 being substantially the same as that shown in FIGURE 4, but with a glazed sash 60 having a slot 61 spaced slightly below the upper edge thereof to thereby provide a finger 62, the finger 62 extending into the slot 51 of the screened frame 50. As will be understood, by this construction sliding movement of the glazed sash 60 relative to the screened frame 50 may be effected, as with the embodiments of FIGURES 1 and 4.

There has been provided a window of pleasing appearance, distinctly different from an esthetic viewpoint from the traditional double-hung windows. The window herein disclosed is a pivoted window which does not require triangular elements for the jambs thereof, and is made of few, economical, readily fabricated and installed parts. Further, the window herein provided permits adequate ventilation and effective weatherproofing, and because it may be securely locked in either the open or closed position, it is particularly suitable for use as a basement window, it thereby being able to remain open at night with security. Not only is the window herein disclosed safe against unauthorized entry, but it may be readily removed for cleaning, or may be readily cleaned from the inside of the building even without removal from the window frame.

It will be obvious to those skilled in the art that various changes may be made without departing from the spirit of the invention and therefore the invention is not limited to what is shown in the drawings and described in the specification but only as indicated in the appended claims.

What is claimed is:

1. A window comprising a header, a sill, and rectangular jambs, said sill having lower bearing means adjacent the outer edge thereof, said header having upper bearing means adjacent the outer edge thereof, said bearing means being on axes extending between said jambs, a glazed sash having at the lower edge thereof means cooperating with said lower bearing means for permitting rotational movement of said sash thereon, a screened frame having at one edge thereof means cooperating with said upper bearing means for permitting rotational movement of said screened frame thereon, said screened frame extending generally inwardly from said upper bearing means, a pair of slots extending in said screened frame generally perpendicularly to the axis of said upper bearing means, each said slot including a generally cylindrical

portion, a slot in the upper edge of said glazed sash having connecting means therein at each end thereof, said connecting means each including a spherical member positioned in the cylindrical portion of a said slot of said screened frame, weather stripping means in the slot of said glazed sash between said connecting means, and weather stripping means along said jambs for engagement by said glazed sash upon rotation thereof to a closed position in which the glazed sash upper edge is adjacent said upper bearing.

2. The window of claim 1, and weather stripping carried by said glazed sash at either side thereof engageable with said jambs.

3. A window comprising a header, a sill, and rectangular side jambs, said sill having lower bearing means adjacent the outer edge thereof, said header having upper bearing means adjacent the outer edge thereof, said bearing means being on axes extending between said jambs, a glazed sash having at the lower edge thereof means cooperating with said lower bearing means for permitting rotational movement of said sash thereon, a screened frame having at one edge thereof means cooperating with said upper bearing means for permitting rotational movement of said screened frame thereon, said screened frame extending generally inwardly from said upper bearing means, a pair of slots extending in said screened frame generally perpendicularly to the axis of said upper bearing means, each said slot including a generally cylindrical portion, connecting means on said glazed sash adjacent each side thereof, said connecting means each including a spherical member positioned in the cylindrical portion of said slot of said screened frame, and weather stripping means along said jambs for engagement by said glazed sash upon rotation thereof to a closed position in which the glazed sash upper edge is adjacent said upper bearing.

4. A window comprising a header, a sill, and jambs, said sill having lower bearing means adjacent the outer edge thereof, said header having upper bearing means adjacent the outer edge thereof, said bearing means being on axes extending between said jambs, a glazed sash having at the lower edge thereof means cooperating with said lower bearing means for permitting rotational movement of said sash thereon, a screened frame having at one edge thereof means cooperating with said upper bearing means for permitting rotational movement of said screened frame thereon, said screened frame extending generally inwardly from said upper bearing means, a pair of slots extending in said screened frame generally perpendicularly to the axis of said upper bearing means, each said slot including a generally cylindrical portion, and connecting means on said glazed sash adjacent each side thereof, said connecting means each including a spherical member positioned in the cylindrical portion of a said slot of said screened frame.

5. A window comprising a header, a sill, and jambs, said sill having lower bearing means adjacent the outer edge thereof, said header having upper bearing means adjacent the outer edge thereof, said bearing means being on axes extending between said jambs, a glazed sash having at the lower edge thereof means cooperating with said lower bearing means for permitting rotational movement of said sash thereon, a screened frame having at one edge thereof means cooperating with said upper bearing means for permitting rotational movement of said screened frame thereon, said screened frame extending generally inwardly from said upper bearing means, said screened frame comprising slot means extending generally perpendicularly to the axis of said upper bearing means, said glazed sash comprising connecting means engageable in the slot means of said glazed sash whereby said glazed sash may be rotated on said lower bearing means to expose more or less of said screened frame.

6. A window as in claim 5, and means for limiting the movement of the upper edge of said glazed sash away from said upper bearing means.

7. A window as in claim 5, and means for limiting the movement of the inner edge of said screened frame away from said lower bearing means.

8. The window of claim 7, said means comprising a block on said jamb.

9. The window of claim 8, and removable means for securing said block in a fixed position on said jamb.

10. A window comprising a header, a sill, and jambs, said sill having lower bearing means adjacent the outer edge thereof, said header having upper bearing means adjacent the outer edge thereof, said bearing means being on axes extending between said jambs, a glazed sash having at the lower edge thereof means cooperating with said lower bearing means for permitting rotational movement of said sash thereon, a screened frame having at one edge thereof means cooperating with said upper bearing means for permitting rotational movement of said screened frame thereon, said screened frame extending generally inwardly from said upper bearing means, laterally facing slot means extending in said screened frame generally perpendicularly to the axis of said upper bearing means, laterally extending connecting finger means secured to said glazed sash and positioned in the slot means of said screened frame for sliding movement therein whereby said glazed sash may be rotated on said lower bearing means to expose more or less of said screened frame.

11. A window comprising a header, a sill, and jambs, said sill having lower bearing means adjacent the outer edge thereof, said header having upper bearing means adjacent the outer edge thereof, said bearing means being on axes extending between said jambs, a glazed sash having at the lower edge thereof means cooperating with said lower bearing means for permitting rotational movement of said sash thereon, a screened frame having at one edge thereof means cooperating with said upper bearing means for permitting rotational movement of said screened frame thereon, said screened frame extending generally inwardly from said upper bearing means, laterally facing slot means extending in said screened frame generally perpendicularly to the axis of said upper bearing means, slot means in the side of said glazed sash having laterally extending connecting finger means in the slot means of said screen frame for sliding movement therein, whereby said glazed sash may be rotated on said lower bearing means to expose more or less of said screened frame.

12. A window comprising spaced upper and lower generally parallel bearing means, a glazed sash having at the lower edge thereof means cooperating with said lower bearing means for permitting rotational movement of said sash thereon, a screened frame having at one edge thereof means cooperating with said upper bearing means

for permitting rotational movement of said screened frame thereon, said screened frame extending generally over said glazed sash, said screened frame comprising slot means extending generally perpendicularly to the axis of said upper bearing means, said glazed sash comprising connecting means engageable in the slot means of said screened frame, whereby said glazed sash may be rotated on said lower bearing means to expose more or less of said screened frame.

13. A window comprising spaced upper and lower generally parallel bearing means, a glazed sash having at the lower edge thereof means cooperating with said lower bearing means for permitting rotational movement of said sash thereon, a screened frame having at one edge thereof means cooperating with said upper bearing means for permitting rotational movement of said screened frame thereon, said screened frame extending generally over said glazed sash, a pair of slots extending in said screened frame generally perpendicularly to the axis of said upper bearing means, each said slot including a generally cylindrical portion, and connecting means on said glazed sash adjacent each side thereof, said connecting means each including a spherical member positioned in the cylindrical portion of a said slot of said screened frame.

14. A window comprising spaced upper and lower generally parallel bearing means, a glazed sash having at the lower edge thereof means cooperating with said lower bearing means for permitting rotational movement of said sash thereon, a screened frame having at one edge thereof means cooperating with said upper bearing means for permitting rotational movement of said screened frame thereon, said screened frame extending generally over said glazed sash, laterally facing slot means extending in said screened frame generally perpendicularly to the axis of said upper bearing means, slot means in the side of said glazed sash having laterally extending finger means in the slot means of said screen frame for sliding movement therein, whereby said glazed sash may be rotated on said lower bearing means to expose more or less of said screened frame.
